UNITED STATES PATENT OFFICE.

EARL R. SIMPSON, OF SALEM, OREGON.

MAIL-BAG CATCHING AND DELIVERING APPARATUS.

1,021,341.

Specification of Letters Patent. Patented Mar. 26, 1912.

Application filed December 29, 1910. Serial No. 599,827.

To all whom it may concern:

Be it known that I, EARL R. SIMPSON, a citizen of the United States, residing at Salem, in the county of Marion, State of Oregon, have invented certain new and useful Improvements in Mail-Bag Catching and Delivering Apparatus; and I do hereby declare the following to be a full, clear, and exact description of the invention, such as will enable others skilled in the art to which it appertains to make and use the same.

The present invention relates to improvements in mail-bag catching and delivering apparatus, and it has for its primary object the provision of an exceedingly simple, and efficient apparatus for automatically effecting the simultaneous delivery of a mail-bag from a moving train to the receiving station, and from the station to the train.

More especially, however, the invention resides in the particular construction of the apparatus located at the station, such apparatus comprising generally, a yielding buffer mounted upon an elevated platform beneath which latter is disposed a cage designed to receive the mail-bag removed from the delivery arm of the car-carried apparatus by its contact with the buffer, the platform being provided with a longitudinal slot through which the bag falls into the cage.

The invention further resides in the provision of a cradle which is movable within the cage and is rocked by a lever lying in the path of movement of the delivery arm of the car-carried apparatus, the actuation of said lever raising the cradle into operative position, and thereby holding the delivered mail-bag against the buffer, until the lever becomes released from engagement with the car-arm, whereupon, the cradle is free to return to its normal position, thus depositing the bag within the cage.

The invention still further resides in the particular construction of the pole to which the platform is secured, and in the particular devices employed for rotating the pole from operative to inoperative position, and vice versa, and for retaining the pole in either position.

The preferred embodiment of the inven-

tion is illustrated in the accompanying drawings in which corresponding parts, or features, as the case may be, are designated by the same reference numerals throughout the several views, wherein:

Figure 1 is a perspective view of the complete invention. Fig. 2 is a front elevation of the apparatus located at the receiving station. Fig. 3 is a top plan of Fig. 2. Fig. 4 is an enlarged vertical section taken through the cage, showing the cradle in its operative position. Fig. 5 is an enlarged detail perspective view of the cradle. Fig. 6 is a detail view of the car-arm. Fig. 7 is a fragmental sectional view illustrating the mounting of the pole.

Referring more particularly to the drawings, 1 designates generally, the mail car which is provided with the usual door opening 2 formed in one side thereof, in which opening is journaled a rotatable supporting bar 3, the movement of which is effected by means of a handle 4 secured to a collar 5 carried by said bar. The collar 5 also carries the crane arm generally designated 6, said arm comprising a pair of rods 7 and 8 arranged at right angles to each other, the outer end 9 of the first-mentioned rod being laterally offset so as to coöperate with the hooked forward portion 10 of the rod 8 in forming a bag receiving seat, the rear portion 11 of said rod 8 forming a support for the bag to be delivered to the apparatus at the receiving station. The crane arm will thus be moved bodily into operative position after a mail bag has been attached to the supporting portion 11, in which position it occupies an approximately horizontal plane, extending directly outward from the door way, being retained in such position by means of a fastening device (not shown) of any preferred type adapted for engagement with one end or the other of the supporting bar.

The complementary apparatus to that above described, or in other words, the apparatus located at the receiving station, consists primarily of a vertical pole 12, an elevated supporting platform 13 secured thereto, and a buffer 14 and cage 15 attached to said platform. The lower end of the pole

extends through bearing openings formed in the top and bottom members 16 and 17 of a box 18 embedded in the ground adjacent the track rails upon which the 5 mail car travels, the extreme lower end of the pole having a reduced diameter, as shown in Fig. 7, this construction resulting in the formation of a shoulder 19 which rests upon the upper face of the bottom 10 member 17 of the box which latter thus serves as a support for the pole. The platform 13, above referred to, is secured directly to the pole at the requisite distance from the ground and is supported by a 15 brace 20 fastened at opposite ends to the pole and the platform. Through said platform is formed a pair of longitudinal slots 21 arranged parallel with and in spaced relation to each other. The buffer 14 is 20 mounted directly between the slots 21 and as shown comprises an open rectangular frame and a net work 22 of interwoven ropes secured thereto, the upper member 23 of said frame terminating at its inner end 25 in a collar which embraces the pole and is secured thereto, while the lower frame member 24 is disposed directly upon the longitudinal connecting strip 25 between the slots 21. The front member 26 of the frame is 30 constructed in two separate sections, whose mutually-adjacent inner ends are arranged in spaced relation to each other, thus forming an entrance to the inwardly extending horizontal channel 27 with which the buffer 35 is provided, this channel resulting from the removal of a portion of the central horizontal strand of rope, and the subsequent attachment of the inner ends of the adjacent upper and lower strands to the horizontal strands on either side of said central strand.

The cage 15 is secured to the under face of the platform directly beneath the slots 21 and comprises a wooden frame work 29 45 rectangular in cross section, and a rope netting 29' secured to the lower edges of the members thereof, the length of the cage being slightly greater than that of the slots 21, whose combined width is likewise slightly 50 less than that of the cage. One of the sides of the cage is provided with a door 30 to permit the mail bags deposited in the cage as hereinafter described, to be removed therefrom.

55 The supporting platform is further provided with a horizontal rock shaft 31 journaled in brackets secured to the under face of the connecting strip 25 above referred to, the forward end of said shaft projecting 60 beyond the front edge of the platform and carrying at such point an operating lever 32. To said shaft is secured a rocker 33 consisting of a pair of spaced arcuate sides 34, whose corresponding ends are connected

by rods 35, the central portion of the rocker 65 being open as shown. The rocker which has a width slightly less than the length of the slots 21 is disposed in its normal or inoperative position completely within the cage. When, however, the operating lever 32 is 70 swung in either direction, one end or the other of the rocker will move upwardly through the corresponding slot and will approach the buffer, as shown in Fig. 4.

The upper member 23 of the buffer frame 75 carries a double hook 36 whose prongs project in opposite directions, one on one side of the buffer and the other on the other side. From either of said prongs is suspended 80 the mail bag to be delivered to the train.

The pole 12 as originally stated is supported in a bearing box 18, is rotated in either direction by means of a laterally projecting handle 37. Secured to and surrounding the pole 12 is a ratchet wheel 52. 85 A wear plate 39 secured to the upper portion 16 of the bearing box 18 supports a casing 54 said casing having a latch member 53 slidable therein and adapted to contact with the teeth upon the ratchet wheel 52, 90 the coil spring 55 holding said latch member in operative position. A spring member 57 is secured to the base of the post by the collar 56, lugs 58 formed upon the casing 54 forming a keeper for said spring member 57. 95 When the receiving apparatus is in operative position the spring member 57 extends toward the track. When a mail bag is received by the device the force of the blow swings the entire device around out of operative position, the catch and ratchet wheel acting as a brake meanwhile. When the device has swung through 180 degrees the spring member 57 is engaged by the keeper lugs 58 and further motion is stopped. By 100 this arrangement the device is permitted to swing and thus take up the shock which it would otherwise experience upon the receipt of a mail bag, at the same time the spring member 57 forms an automatic means 110 for locking the device in inoperative position.

The platform upon which the buffer is mounted is reached by means of a ladder 51 carried by the pole. 115

The operation of the complete apparatus is described as follows. As the mail car approaches the station, the postal clerk raises the crane arm 6 into its operative position and suspends the mail bag from the supporting portion 11 thereof. At the same time, the postal clerk at the receiving station attaches a mail bag to one or the other of the prongs of the hooks 36 according to the direction in which the approaching car 120 is traveling. As the car passes by the station the hook portion 10 of the crane arm 125 will pass through the channel 27 formed

in the buffer, and will remove the bag from the hook 26, while at the same time, the contact of the mail bag carried by the crane arm with the buffer will remove the bag from 5 said arm as will be apparent. Prior, however, to the removal of the mail bag from the crane arm, the lever 32, which extends normally in the path of said arm will be struck thereby and tripped, thus rocking 10 the shaft 31 and swinging the corresponding end of the rocker through the adjacent slot 21. As the mail bag is removed from the crane arm, it is engaged by said rocker end and thus held from bounding off the 15 platform. As the crane arm passes beyond and out of contact with the trip lever, the rocker assumes its normal position under the weight of the mail bag which latter falls through the open central portion of the 20 rocker onto the bottom of the cage, passing through the slot 21 in the platform during such return movement of the rocker.

From the foregoing, it will be apparent that the transfer of the mail bags from 25 the car to the receiving station, and vice versa, is effected automatically as the car passes the station; that the provision of the channel in the buffer and of the two pronged hooks enables the station mechanism to be 30 operated, without changing its position irrespective of the direction in which the mail car is traveling; that the provision of the rocker has the effect of preventing the mail bag delivered to the buffer from 35 bounding off the platform; and that the cage serves to retain the delivered mail bag and to prevent access thereto by unauthorized persons. It will also be apparent that the supporting platform and with it the 40 crane and cage may be moved into and out of operative position by rotating the pole in one direction or the other, the pole being retained in its adjusted position by the engagement of the latch end in one or the 45 other of the sockets 40.

Owing to the fact that the body portion of the buffer is formed of rope, the mail bag will suffer no injury from contact therewith, the ropes being sufficiently slack to 50 permit the netting as a whole to yield slightly. The employment of netting as a bottom for the cage likewise prevents injury to the mail bag delivered thereto from rain which otherwise would settle in the 55 cage.

The invention is not intended to be limited to the exact details of construction shown and described as modifications and changes may obviously be made within the scope of 60 the appended claims.

What is claimed is:

1. A mail-crane, comprising, in combination, a horizontal platform provided with a pair of parallel slots arranged in spaced re-

lation to each other; a cage disposed directly beneath said slots; and a vertical buffer mounted upon said platform in the space between said slots and disposed parallel with the same. 65

2. A mail-crane, comprising, in combination, a platform provided with a slot; a vertical buffer mounted upon the platform adjacent said slot; and a retaining member movable through said slot into engagement with a mail-bag delivered to the buffer. 70 75

3. A mail-crane, comprising, in combination, a platform provided with a slot; a vertical buffer mounted upon said platform adjacent said slot; a shaft carried by the platform and disposed parallel with said 80 slot; a retaining member secured to said shaft; and means for rocking said shaft, to move said member through the slot into engagement with the mail-bag delivered to the buffer. 85

4. A mail-crane, comprising, in combination, a platform provided with a slot; a vertical buffer mounted upon the platform adjacent said slot; a horizontally-disposed rock shaft secured to the under face of 90 said platform parallel with said slot; a retaining member secured to said shaft; and a trip lever secured to the outer end of said shaft, for rocking the same, to move said member through said slot into engagement 95 with a mail-bag delivered to the buffer.

5. A mail-crane, comprising, in combination, a platform provided with a slot; a vertical buffer mounted upon the platform adjacent said slot and provided with an 100 opening extending inwardly from the front edge thereof; and a retaining member carried by said platform and movable through said slot into engagement with a mail-bag delivered to the buffer. 105

6. A mail-crane, comprising, in combination, a platform provided with a pair of parallel slots arranged in spaced relation to each other; a vertical buffer mounted upon the platform in the space between 110 said slots and disposed parallel with the same; a rock shaft secured to the under face of said platform directly beneath said buffer; a retaining member secured to said rock shaft; and a lever secured to said shaft, for rocking the same, to move either end of said member through the corresponding slot into engagement with a mail-bag delivered to the buffer. 115

7. A mail-crane, comprising, in combination, a platform provided with a pair of parallel slots arranged in spaced relation to each other; a vertical buffer mounted upon said platform in the space between said slots and disposed parallel with the same; a rock shaft secured to the under face of the platform directly beneath said buffer; a retaining member secured to said shaft and 120 125

having its opposite ends upturned; and means for rocking said shaft, to move either end of said member through the corresponding slot into engagement with a mail-bag delivered to the buffer.

8. A mail-crane, comprising, in combination, a platform provided with a slot; a vertical buffer mounted upon the platform adjacent said slot; a cage disposed directly beneath said slot; and a retaining member

disposed normally within said cage and arranged for movement through said slot into engagement with a mail-bag delivered to the buffer.

In testimony whereof, I affix my signature, in presence of two witnesses.

EARL R. SIMPSON.
